UNITED STATES PATENT OFFICE.

WALTER S. MOODY, OF LYNN, MASSACHUSETTS, ASSIGNOR TO THE GENERAL ELECTRIC COMPANY, OF NEW YORK.

ELECTRICAL TRANSFORMER.

SPECIFICATION forming part of Letters Patent No. 567,250, dated September 8, 1896.

Application filed March 30, 1896. Serial No. 585,334. (No model.)

To all whom it may concern.

Be it known that I, WALTER S. MOODY, a citizen of the United States, residing at Lynn, in the county of Essex, State of Massachusetts, have invented certain new and useful Improvements in Transformers (Case No. 316,) of which the following is a specification.

This invention relates to transformers, and has for its object to provide an improved core for transformers formed of built-up groups of laminæ constructed and arranged as hereinafter set forth and claimed.

Referring to the accompanying drawings, Figure 1 is a perspective view in elevation of a core constructed in accordance with this invention. Fig. 2 is a detail view of one of the laminæ forming the core. Fig. 3 is a perspective view in elevation of a modified form of core incomplete. Figs. 4 and 5 are detail views of laminæ forming the core. Fig. 6 is a perspective view of a modification, showing a portion of the laminæ. Fig. 6^a is a side view in elevation and partly in section showing part of the casing removed of a transformer constructed in accordance with this invention. Fig. 7 is an end view thereof in elevation. Fig. 8 is a top plan view. Fig. 9 is a view of the top cap of the core. Fig. 10 is an edge view thereof, partly broken away. Figs. 11, 12, and 13 are edge, plan, and transverse sectional views of the bottom supporting-plate of the core.

Referring now to Fig. 1, one form of building up the core is as follows: Sheet-iron is cut up into strips or laminæ of two sizes, consisting of long pieces 1 and short pieces 2. These pieces are rectangular, and thereby there is no waste of material in cutting. The long pieces 1 are assembled in small groups of three or four pieces, more or less, each group overlapping an adjacent group at one end and being correspondingly shorter than its neighbor at the other end; or, in other words, the groups are alternately mismatched, so that when the laminæ have been built up to the desired thickness there is formed at each end a tongue-and-groove arrangement, as shown. The winding 3 is then placed about the longer bundle of laminæ 1, as shown in Figs. 6^a, 7, and 8, the secondary coil being wound next to the core with the usual insulation inter-

posed and the primary being wound without the secondary so as to remove it far away from the core. The winding is effected by clamping the ends of the bundle of laminæ in a frame of a winding-machine, the work of insulating and winding being much facilitated in this way. Both upright or longer portions of the core are so wound, and the primary and secondary coils may therefore be conveniently connected in multiple or in series, respectively, to accommodate themselves to the potential of the circuits to which they are to be connected. The windings and insulation of the core also serve to hold the laminæ together after the core is removed from the frame of the winding-machine.

To complete the core of the transformer, two of the aforesaid wound bundles of long laminæ are placed at a suitable distance apart, and the tongue-and-grooved ends thereof are provided with bundles of short laminæ 2, as shown in Fig. 1, their ends filling the grooves on one side and abutting against the ends of the long laminæ on the other side, the groups thereby breaking joint and providing a magnetic core having a low magnetic resistance.

The sections of the core are locked and held in position by the metallic end caps 4 5, which are slipped over the ends of the core, and are separated therefrom by wooden strips 6 and wooden wedges 7, driven in to hold the parts firmly in place. The bottom cap 5 has feet or projections 8, which rest on the bottom of the transformer-casing 9, and the top cap 4 has lugs 10, which rest upon a ledge or flange 11 of the casing 9, the core being secured to the casing by bolts and nuts 12, engaging some of the lugs 10.

In the modification shown in Fig. 3 the construction is similar to that in Fig. 1, except that the bundles of long pieces 13 are not mismatched or overlapping with respect to each other, but are of equal length, with a bundle of short laminæ 14 inserted between each pair of bundles of long laminæ 13, forming grooved joints at the ends of the core, in which rest the ends of the bundles of short laminæ 14. By means of this arrangement open air-spaces 15 are provided at the ends of the core. The cross-section of the metal would therefore be reduced at this point; but provision is made

for that by increasing the thickness of the bundles of laminæ forming the ends of the core. An advantage of the ventilating-openings lies in increasing the cooling effects on the structure. The transformer-casing may or may not be filled with oil, as desired. It will be noted that but two sizes of laminæ are required in the construction of the core. If desired, however, in the construction of Fig. 5 10 3, three sizes of punchings may be employed—viz, the longer and shorter laminæ of the sides and the laminæ of the ends of the core being each of a different size.

To facilitate the assembling of the side laminæ, holes 16 are punched therein, those in Fig. 1 being located at uneven distances from the ends of the laminæ. A number of laminæ, with their holes matching, are slipped over suitably-spaced pins 16', and so on in 15 20 25 30 35 40 45 50 55 groups to form the offset arrangement described. Before being wound with coils the bundle of sheet-iron laminæ assembled to the desired thickness are provided with U-shaped caps 17, of strong red fiber paper, having its inner surface covered with shellac, said caps being placed over the sides, and after the bundle is forced into a compact mass in a powerful press the shellacked paper is secured to the core and to the opposite cap by being subjected to the pressure of a heated iron, which softens the shellac and causes the parts to adhere firmly. In smaller sizes of transformer each lamina may overlap its neighbor instead of overlapping by groups. Further, in assembling the side laminæ it should be added that these pins 16' are made of wood, and when the sheets are piled up upon the plates of the press or bed of the press the pins 16' pass through openings suitably provided in the upper plate of the press during compression, and after the strong fiber paper has been shellacked in place to hold the laminæ in their compacted position the pins 16' are cut off flush with the surface. By means of these pins 16' the slipping of the individual sheets of the core over each other is prevented and the bundle remains square or rectangular. Moreover, and of still greater importance, this mode of working obviates the use of insulated metallic bolts to hold the laminæ together after compression, which must needs have a nut forming a projection which breaks up the surface and requires additional insulation, whereas the wooden pins and paper-fiber together make an advantageous substitute.

When the bundles of laminæ have been arranged in proper order—that is, with alternately-overlapping ends, as described—and

are forced compactly together in a powerful press, the grooves are, of course, nearly closed up, more especially in the case where the number of sheets composing one group of laminæ is small. This makes the operation of inserting the end laminæ, after the said cores have been properly wound with their coils, more tedious, because the workman is compelled to carefully count the number of sheets constituting each group. To avoid this delay and afford a quick means of determining the proper place for the insertion of the end laminæ, one corner of each lamina is cut off, as at 17, and during assembling they are matched so that these cut-off corners 17 are found in line at the bottom of the grooves 70 75 80 85 90 95 100 formed between the adjacent sets of laminæ, and thus make it easy for the workman to quickly divide the laminæ into their proper groupings when he is inserting the end laminæ, the cut-off corners 17 being readily discernible by the eye, and the end laminæ are of course inserted as groups comprising the same number of sheets as the side laminæ or bundles.

Considering the transformer electrically, it will be noted that the loss due to "leakage magnetism" is reduced to a minimum owing to the relatively great distance between the ends of the core.

What I claim is—

1. A transformer consisting of a built-up core, having its sides composed of bundles of metallic laminæ with overlapping ends, and its ends composed of bundles of metallic laminæ breaking joint with the sides, shellacked fiber paper wrapped around the side laminæ, insulating pins securing the latter together, and windings about the sides of the core.
2. In an electrical transformer the combination of, a core or coil carrying portion consisting of an assemblage of rectangular sheet-iron laminæ, each sheet having spacing-holes situated at points unequally distant from the ends of the sheet, spacing and stiffening pins of non-magnetic insulating material, such as wood, in said holes having a flush surface with the outer face of the sheets, a fibrous insulating covering or wrapping serving to retain said sheets in their compressed relation as assembled upon said pins, inducing and induced windings upon said core, and bundles of sheet-iron laminæ joining the ends of said core and adapted to complete the magnetic circuit, as described.
